ANTIGLARE HEADLIGHT ATTACHMENT

George A. Rice, Schenectady, N. Y.

Application March 27, 1934, Serial No. 717,648

2 Claims. (Cl. 240—48.6)

This invention relates to an attachment for headlights and more particularly to a means in the form of an attachment to prevent glare from the headlight.

5 An object of this invention is to provide a shield which can be mounted on any conventional headlight bulb and which embodies a construction whereby the upwardly directed light rays from the reflector and the direct light rays from the 10 source of light will be prevented from causing glare to oncoming vehicles.

Another object of this invention is to provide 15 an anti-glare attachment of this type which can be constructed out of sheet metal which may be suitably formed as by stamping or the like so that it will snugly engage about a portion of the light bulb and which includes a means whereby the shield may be yieldably held on the bulb so that in the event the light bulb burns out, the attachment 20 can be removed and placed on a new bulb.

The above and various other objects and advantages of this invention will in part be described and in part be understood from the following detailed description of the present preferred embodiment, the same being illustrated in the accompanying drawing wherein:—

Figure 1 is a detail side elevation of a light bulb having a device constructed according to the preferred embodiment of this invention, mounted thereon, the device being shown in longitudinal section.

Figure 2 is a plan view of the device in blank form.

Figure 3 is a detail front elevation of the device. Figure 4 is a sectional view taken on the line 6—6 of Figure 1.

Figure 5 is a sectional view taken on the line 5—5 of Figure 1.

Figure 6 is a sectional view taken on the line 40 6—6 of Figure 3.

Referring to the drawing wherein like numerals of reference designate corresponding parts throughout the several views, the numeral 10 designates generally a light bulb which is provided with a base 11 adapted to engage in a conventional light bulb socket, as is used in motor vehicles or the like. This light bulb 10 is provided with opposed outstanding pins 13 for engagement in the usual bayonet slot provided in the socket.

In order to provide a means whereby the upwardly directed and horizontally directed light rays from the headlight associated with the light bulb 10 may be deflected so that they will not cause glare in the eyes of approaching drivers,

I have provided a shield structure comprising a concave plate 12 having a shank 14 and a base structure 15 which is adapted to be secured to the light bulb about the base 11 by means of a spring or yieldable member 16.

The concave plate 12, in the present instance, is made out of metal of a suitable thickness such that it may be readily made initially in template form and then pressed or otherwise formed, as shown in the drawing. The upper end of the shield portion 12 is cut out, as at 17, so that the shield 12 will engage about a considerable portion of the light bulb 10 at the forward end thereof so as to prevent the horizontal or direct light rays from being projected forwardly of the vehicle while at the same time permitting downwardly directed reflected light rays to freely pass forwardly of the vehicle.

The shank 14 has an elongated detent 18 which acts as a bracing or strengthening means so that relatively light weight metal may be used which, on account of the strengthening member 18, will snugly engage about the lower portion and the front portion of the light bulb 10. The base 15 comprises a pair of curved returned arms 19 which are connected together at their lower portions by means of a forwardly extending plate 20 secured at its forward portion as by solder 21 to the lower side of the rear of the shank 14. The spring 16 engages the arms 19 at their uppermost portion, being looped or otherwise secured thereabout.

As will be shown from Figure 2, the shield or body portion 12 is constructed integral with the shank 14 and with the arms 19 as well as the plate or connecting member 20. The arms 19 are formed in blank form by punching out a circular opening in the rear portion of the plate, which rear portion is preferably wider than the width of the shank 14 so that these curved arms 40 will form an open socket to receive the base portion 11 of the light bulb. The attachment is placed on the lower side of the light bulb 10 and by reason of the spring 16, the attachment can be suitably adjusted after the bulb 10 is engaged 45 with the usual socket within the reflector of the head light. Preferably, the inner surface of the shield 12 is a reflecting surface which may be formed by either polishing or plating the surface and the outer surface of the shield 12 may be 50 opaque so that it will not reflect any light rays from the lower portion of the reflector.

As will be noted from Figures 3 and 6, the shield 12 is provided on its front and lower surfaces with flat reflecting faces 22 so that the light rays re- 55

flected by the inner surface of the shield will be directed toward the upper portion of the reflector from which point the light rays will be projected in a forward and downward direction rather than upward direction. The shield herein disclosed will, therefore, not only prevent the upwardly directed rays from reaching the eyes of oncoming drivers but will concentrate the rays in the upper portion of the reflector, from which point they will be directed forwardly and downwardly, thereby increasing the lighting of the road ahead of the vehicle.

What is claimed is:—

1. A device as set forth, comprising a concave plate having an arcuate upper edge portion, a reduced shank carried by the rear of said plate, bracing means integral with said shank, a pair of V-shaped supporting arms having curved inner edge portions carried by said shank, said arms

engaging about the base of the light bulb, bracing means integral with said shank and each arm, and a spring secured to the converging portions of said arms and engaging about the base of the light bulb.

2. A device as set forth, comprising a substantially concave plate, flat reflecting faces carried by the plate at the forward and lower portion thereof, a reduced shank carried by the rear of said plate, bracing means integral with said shank, a pair of V-shaped supporting arms having curved inner edge portions carried by said shank, said arms engaging about the base of the light bulb, a bracing means integral with said shank and each arm and extending forwardly of said arms, and a spring secured to the converging portions of said arms and engaging about the base of the light bulb.

GEORGE A. RICE.
